UNITED STATES PATENT OFFICE.

FREDRICK H. BOBIER, OF MOUNT GREEN, SASKATCHEWAN, CANADA.

BINDER-TONGUE TRUCK.

1,218,516.

Specification of Letters Patent.

Patented Mar. 6, 1917.

Application filed June 13, 1916. Serial No. 103,563.

To all whom it may concern:

Be it known that I, FREDRICK H. BOBIER, a subject of the King of England, residing at Mount Green, in the Province of Saskatchewan, Dominion of Canada, have invented certain new and useful Improvements in Binder-Tongue Trucks; and I do hereby declare the following to be a full, clear, and exact description of the invention, such as will enable others skilled in the art to which it appertains to make and use the same.

This invention relates to a binder tongue truck.

15 The primary object of my invention resides in the provision of a truck which is so constructed that the operator will be enabled to turn the binder on a square corner so as to facilitate the cutting of the grain.

20 A further object of the invention resides in so constructing the truck that the wheels will automatically follow the direct line of draft.

With these and other objects in view, such 25 as will appear as my description progresses, my invention comprises the combination and arrangement of parts as set forth in and falling within the scope of the appended claims.

30 In the drawing:

Figure 1 is a plan view of a device constructed in accordance with my invention;

Fig. 2 is a side elevation thereof;

Fig. 3 is a vertical sectional view on line

35 3—3 of Fig. 1, and

Fig. 4 is an enlarged detail of one of the wheel supporting castings.

In the drawing, I have illustrated a portion 40 of a binder which includes a stub tongue 1 which is braced by a suitable brace 2. Extending downwardly from this tongue 1 is a standard 3 which is connected to a main tongue 4 by a ball and socket connection 5. Secured and extending at right angles to the

45 main tongue 4 is a pair of bars 6. Pivotaly mounted between the ends of these bars on bolts 7 are castings which include tubular bearing members 8 and wheel spindles 9 on which dust caps 10 are mounted which are

50 adapted to protect the inner sides of the hubs of the wheels. Each of these tubular

bearing portions is provided with a forwardly extending arm 11, the forward ends of which arms are connected together by a rod 12. One of the castings is provided with 55 an arm 13 which extends at right angles to the arm 11 and is connected to the stub tongue 1 by a rod 14. Wheels 15 are mounted on the spindles 9 and are provided with hard grease cups 16 by means of which the 60 spindles may be oiled. The ends of the hubs of these wheels are provided with chambers in which dust caps 17 are mounted and the rims of the wheels are provided with ribs 18 which prevent the skidding of 65 the wheels. Each of the castings before described, is provided with a hand oiler 19 so that the movement of the castings on the bolts 7 will be facilitated.

It will be seen that with this construction 70 when the main tongue 4 is turned the wheels on the spindles 9 will follow the direct line of draft and when a corner is turned the bull wheel will act as a pivot causing the grain wheel to travel backward and allowing 75 the binder to proceed cutting a full swath and leaving a perfect square corner. It will be further seen that I have provided means for protecting the wheels so that the bearings will not be worn because of the presence 80 of dust or other foreign material.

While I have illustrated and described a particular embodiment of my invention, it has merely been for the sake of convenience and I do not wish to be limited to that particular embodiment as it is obvious that numerous changes may be made in the details of construction without departing from the spirit of the invention or exceeding the scope of the appended claim. 90

What I claim is:

The combination with the stub tongue of a binder, of an arm depending therefrom and having a ball and socket connection thereon, a main tongue connected to the arm 95 by the ball and socket connection, a pair of bars secured to the main tongue and extending transversely thereof, bolts extending between the ends of the bars, wheel spindles having bearing members mounted on said 100 bolts, the said spindles being adapted to turn in a horizontal plane, arms extending

outwardly from said bearing members, a rod connecting said arms, one of said bearing members having an arm extending at right angles to the first mentioned arms and a rod 5 connecting the last mentioned arms and the stub tongue.

In testimony whereof, I affix my signature, in the presence of two witnesses.

FREDRICK H. BOBIER.
